UNITED STATES PATENT OFFICE.

JEAN JACQUES HEILMANN, OF PARIS, FRANCE.

DIRECT-ACTING EXPLOSION-TURBINE.

1,171,121.

Specification of Letters Patent. Patented Feb. 8, 1916.

Application filed March 21, 1911. Serial No. 615,877.

To all whom it may concern:

Be it known that I, JEAN JACQUES HEILMANN, citizen of the French Republic, residing at Paris, in the Department of the 5 Seine, France, have invented certain new and useful Improvements in Direct-Acting Explosion-Turbines, of which the following is a specification.

Heretofore explosion turbines, so called, 10 have not been in reality true explosion or internal combustion turbines, inasmuch as the principle upon which they are based is similar to that of gas turbines in which the expansion of the gases is utilized for actuating the movable elements or rotors. In 15 other words, until now in explosion turbines the explosive mixture has occupied an explosion chamber independent of the rotor, and after being ignited in this independent 20 chamber, the products of combustion have been permitted to act expansively on the vanes of the rotor.

In order that a turbine may really be termed an internal combustion turbine it 25 should be comparable to an internal combustion engine.

This invention hence has reference to an explosion turbine or internal combustion turbine the mode of operation of which can 30 in certain ways be compared with that of an internal combustion engine.

The principle involved in the construction 35 of this turbine essentially consists in the more or less momentary and repeated formation of one or more explosion chambers or pockets, by means of parts movable with respect to each other, said parts having cavities and conduits therein adapted to co-act to form the chambers aforesaid when mo- 40 mentarily placed in communication with each other. The action of these parts is automatic and in the preferred form of device is due to the rotation of an intermediate rotor and relatively fixed central and outer 45 elements or stators.

Any suitable method or means of introducing the explosive mixture into the so formed explosion chamber, as well as of exhausting the products of combustion there- 50 from, and any arrangements for igniting the said mixture in said chamber or chambers, may be employed; so that I do not wish to be limited to such features in any way, other than by the scope of the appended 55 claims. By way of exemplification the pro-

duction of the explosive mixture and the exhaust of the products of combustion may be effected by either the fixed central or the exterior portion, or by the rotor, and the igniting devices may be arranged in one 60 of the fixed portions, or in the rotor, the ignition of the mixture being effected at the instant when the co-operating cavities which together constitute a given explosion chamber are in chamber-forming relationship, it 65 being supposed that the conformation of the walls of the explosion chambers is such that a given portion of one of said chambers pertaining, for example, to the fixed central structure constitutes, when compared to re- 70 ciprocating engines, the bottom or head of a cylinder of an internal combustion engine, while the portion of the said explosion chamber pertaining to the rotor constitutes, in effect, the piston. The practical realiza- 75 tion of these secondary questions as well as that of the distribution of the ignition, of the cooling, and that of the backward run- 80 ning, or driving of the turbine rotor, also forms part of, or may be regarded as within the purview of, the present invention; which relates not alone to the provision of explo- 85 sion pockets of such shape, in a plurality of fixed and movable elements, as will drive one at least of said elements through the action of the explosion gases thereon, but, further, of the turbine, complete and as a 90 whole.

In the drawings which form a part hereof and in which like characters designate like 95 parts throughout the several views, I have exemplified a preferred form of my invention. It is to be understood, however, that many changes and modifications may be made therein within the purview of my in- 100 vention and I hence desire to be limited only by the scope of the claims appended hereto.

Referring to the drawings: Figure 1 is a side elevation of the turbine and its accessory parts. Fig. 2 is a vertical longitudinal 105 section of the turbine proper. Fig. 3 is a transverse section of said turbine. Figs. 4, 5 and 6 are detail views of the parts which form the explosion chambers, used in the forward running or driving of the mechanism, said views showing respectively various phases of the formation of such chambers; to wit, the disposition of said parts for admission, explosion and exhaust. Figs. 7, 8 and 9 are similar views showing the po- 110

sition of similar parts used in the backward driving of the mechanism. Figs. 10, 11 and 12 are diagrammatic views showing a method of distributing the explosive mixture to the explosion chambers for simultaneous ignition therein. Fig. 13 is a diagrammatic view of a modification, showing a means for regulating the admission. Figs. 14, 15 and 16 are diagrammatic views showing a preferred means for distributing the explosive mixture to the respective chambers for the consecutive ignition of charges of said mixture therein.

In general, as shown in Figs. 2 and 3, the preferred turbine construction can be regarded as being made up of the following six distinct parts: An outer casing; preferably fixed. Means for distributing the explosive mixture to the explosion chambers. The rotor of the turbine; preferably a cylinder arranged concentrically between the casing and the distributing means, and provided with openings for the purpose of assisting in the formation of the explosion chambers, these said openings taking the place, in the operation of the mechanism, of the blades or vanes of known turbines. Means for admitting the explosive mixture to the distributing means aforesaid at proper times. Means for regulating the supply of explosive mixture. Means for collecting the exhaust gases after they leave the explosion chambers. These parts constitute the primary and practically essential elements of the turbine. The other parts such as those controlling the ignition, the compression of the air, the circulation of the cooling water and so on, are secondary in importance and may be of any suitable and desired construction.

Referring to the drawings, 1 is the cylindrical casing, fastened by any suitable means to a frame, 2 the fixed drum provided with channels 3 introducing the explosive mixture to the distributing chambers, 4 is the rotor situated concentrically between 1 and 2 and mounted on ball bearings 5 and 6, the axial thrust being carried, for example, upon a ball thrust-bearing 7. The explosion chambers are formed by the momentary juxtaposition of openings 8, passing through the walls of the rotor 4, with cavities 9 formed on the surface of the distributing drum 2 and into which open out the channels 3, and with cavities 10 formed on the interior surface of the casing 1, exhaust channels 11 passing from these openings and conducting the products of combustion into the collector 12 from where they are evacuated. The arrangement of the openings 8 and of the cavities 9 and 10 is such as to present two distinct groups of explosion chambers intended for the purpose of permitting either the forward running or the backward running of the rotor,

according as the explosive mixture is sent to one or the other group. This result is attained by simply reversing the position of the openings 8 and cavities 9 and 10, differentiating the one group from the other 70 as may be seen from an examination of the Figs. 4, 5 and 6 which show the disposition of the walls of the explosion chambers used in the forward driving of the rotor, and Figs. 7, 8 and 9 which show 75 the disposition of the walls of the chambers used for backward running.

It is evident that the shape and the capacity of the elements 8, 9 and 10 forming the chambers, as well as the number of the latter may be varied as desired, and that it is also possible to vary the combination in the grouping; for example by arranging three groups of explosion chambers, two of which are for the forward running, i. e. 85 of similar arrangement to Figs. 4, 5 and 6, and one group for the backward running, similar to the arrangement of Figs. 7, 8 and 9. The number of groups may be any desired, i. e. four groups, six groups and so 90 on, one half of which, for example, will be for forward running and the other half for backward running.

The admission of the explosive mixture into the distributing drum 2 is effected by 95 means of the admission tube or sleeve 13 provided with openings 14. This tube in this case turns or rocks alternately in one direction and then in the other, thus bringing at definite intervals the openings 14 therein, 100 opposite the channels 3 which permits the explosive mixture in the interior of the sleeve 13, to pass into the distributing drum 2, and from there into the explosion chambers 8, 9 and 10.

The sleeve 13 may be actuated in any suitable manner, being rocked for example, by means of a cam wheel 15 driven by a wheel 16, the latter being keyed to the shaft of the magneto; the cam raising a tappet 18 is 110 carried by the sleeve 13. The return of the said tube to its original position, when thus driven therefrom, is effected by means of a spring 19 or in any other suitable manner. The admission and closed portions of this 115 tube are shown in the drawings in Figs. 10 and 12. The regulating of the amplitude of the displacement of the tube 13 can be effected as shown in Fig. 13 by advancing or drawing back the tappet 18.

When the admission tube or sleeve 13 is continuously rotated, the arrangement shown in Figs. 14, 15 and 16 will be employed, in which it will be seen that the continuous rotation of the sleeve 13 is effected by the 125 wheel 15, the cam of which has been dispensed with.

The admission and the regulation of the delivery of the air and the gases may be effected by means of a cylindrical plug 20, 130

which in the present instance carries tubes 21, one upon either side, or rather end, thereof, these tubes cover the admission openings 14, of the sleeve 13 when the said plug is in its neutral, or in this instance, median, position shown in Fig. 2. The plug 20 is provided with radially directed conduits 22 preferably of variable sections, said conduits being in communication with a central tube 23 which conducts air under pressure. Cross channels 24 which may be simply annular grooves around the cylindrical surface of the plug, open outwardly preferably immediately adjacent the mouths of the conduits 22, the gaseous fluid being introduced into these channels 24 through the instrumentality of a series of small pipes 25 arranged around the central tube 23, and being parallel to said tube and to the axis of the turbine; channels 24 being in communication with the pipes 25, and the latter extending directly through the plug 20. By means of this arrangement the gases are drawn in after the manner of a Giffard injector by the air under pressure flowing out of the conduit 22 into and through the slots or openings 14 into the respective channels 3 of the distributor 2. The regulation of the supply is effected by longitudinally displacing the plug 20 in the admission tube 13 so as to cause the openings of the conduits 22 to coincide more or less with the admission openings 14, according to the supply required and accordingly as these openings 22 are situated opposite the admission openings 14 corresponding to the one or the other group of explosive chambers, the forward or backward driving of the rotor will be effected. The regulation of the quantity of air may be effected in any desired manner, for example, by means of a damper or throttle valve 26 operated by a rod 27, and the displacement of the plug 20 can be effected by means of a lever 28 and a rod 29.

45 The ignition of the explosive mixture contained in the explosion chambers 8, 9, 10 is effected by spark plugs 30 situated at proper points in the distributing drum 2 and supplied with current coming from the magneto 17. The rate of speed of this magneto as well as the type of distributor will evidently depend on as to whether the sparks of the plug 30 have to be produced for a simultaneous or consecutive ignition according to the method adopted. The magneto 17 can be driven by means of shafts 31 and 32 gear wheels 33 and a helicoidal gear 34, driven from the gear 35 keyed to the shaft 36 of the rotor 4, gear 35 also driving a second shaft 55 37 by means of a gear 38.

The cooling of the fixed parts 1 and 2, and of the rotor 4 is effected by water chambers 1', 2' and 4', and by a system of pipes 30, 40, 41 controlled by a rotary pump 42 keyed to the prolongation of the shaft 32. This

method of cooling suffices to prevent the parts adjoining the explosion chambers 8, 9, 10 being heated to red heat.

The compressed air introduced into the central channel 23 can be supplied from any source whatever, preferably by the turbine itself, for example, by means of pumps 43 the cylinders of which are arranged in tandem and the pistons of which are actuated by eccentric cams 44 or cranks mounted on the shaft 36 of the rotor. The air is compressed into a reservoir 45 and is introduced into the tube 23 of the plug 20 by means of a pipe 46. The driving parts are inclosed in a casing 47.

The above described gas turbine operates in the following manner: In Figs. 3 and 5, the rotor 4 is shown in such a position that the chambers 8 have not yet entirely reached the exhaust chambers 10, while they make connection, on the other hand, at their inner ends with the enlargements of the chambers 9 of the admission channels 3. At this particular instant, the explosions in each of the chambers formed by the chambers 3, 9 and 8, will take place. However, since the rotary slide valve, as shown in Fig. 2, closes channels 3 at their inner ends, none of the highly compressed gases of combustion will escape, but these gases will exert a uniform pressure on the walls of the chambers 3, 9 and 8, without causing the rotation of the rotor. The theory of the operation depends on causing these explosions to take place in the perfectly closed chambers with the end in view of letting the highly compressed gases of combustion suddenly escape during the rotation of the rotor, into the chambers 10. It is therefore necessary that the rotor be given, when in the position shown in Fig. 2, a rotary motion in order to bring the outer ends of the chambers 8 containing the gases of combustion into connection with the exhaust chambers 10, and it is for this purpose that the chambers 9 are arranged in the inner stator 2, which chambers constitute enlargements of the admission channels 3. These enlargements or chambers 9 insure the connection between the explosion or combustion chambers 8 with the channels 3 for an extended period of time, and thus the admitted mixture of explosive gases will exert an action upon the wall surfaces of the chambers 8 for a corresponding period. At the instant when the rotor 4 is in such position that the channels 8 make their first connection with chambers 9, the compressed gas mixture flowing through the channels 3 exerts a jet-like direct pressure upon each of the respective wall surfaces of the chambers 8, whereby a rotation of the rotor is brought about in the direction of the arrow shown in Fig. 4. As soon as the chambers 8 and 9 (see Figs. 3 and 5) are directly opposite each other, the further supply of

gas mixture is cut off through the rotary slide valve 13. However, the rotor will still rotate, due to the momentum caused by the impetus received from the pressure of the 5 gas mixture upon entering the chamber. The explosion will take place within the chambers 8 during this rotation and the rotor will, due to its momentum, be brought so far forwardly that the chambers 8 containing 10 the highly compressed gases of combustion, reach chambers 10. At this moment these highly compressed gases of combustion will escape suddenly from all of the chambers 8 into all of the chambers 10, 15 whereby through the heavy reactionary pressure, the rotor is further turned around in the direction of the arrow until the chambers 8 reach the nearest chambers 9 of the inner stator, when a new mixture of compressed 20 gases is admitted which will exert a corresponding jet-like pressure upon the walls of the chambers 8. This operation is repeated until the turbine has run up to speed.

25 It is possible to give a sufficiently heavy impetus to the rotor through the back-pressure of the explosive mixture and through the simultaneous action of the centrifugal power of the rotor which acts like a heavy 30 fly-wheel when the turbine is running at speed, but it is deemed more suitable to produce the absolutely necessary partial rotation required at the instant of explosion through a directly acting pressure medium, 35 that is, through the pressure of compressed explosive mixture upon the front surfaces of the chambers 8.

Where there are two groups of explosion chambers, one for forward and the other for 40 backward running the products of combustion are more rapidly exhausted through the openings 11 into the collector 12 owing to the atmospheric depression occasioned and constantly maintained in the said collector by means of the other group of 45 explosion chambers for the backward running, the said group acting like a rotary suction pump. A reverse working or mode of operation takes place when the turbine is running 50 backward, that is to say when the plug 20 coincides with the openings 14 of the tube 13 and the openings 3 of the opposite group (Figs. 7, 8 and 9) in which case the group of chambers used as explosion chambers 55 during the forward running will occasion the atmospheric depression in the collector 12.

The number of explosions may be varied as desired, for example on one complete revolution of the rotor 4 there may be as many admissions and explosions as there are explosion chambers.

A device for regulating the speed of the turbine may be employed if necessary, for 60 example a ball regulator or centrifugal gov-

ernor acting on the throttle valve 26 or even on the amplitude of the rotary movement of the tube 13.

It is evident, as has already been stated, that various modifications may be introduced in the arrangement of the component parts of this turbine as well as in the parts themselves without in any way affecting the principle of the invention, essentially involving the combination of two preferably 75 fixed parts and an intermediate movable part, said parts periodically coöperating momentarily to form and un-form explosion chambers into which the explosive mixture is introduced, the simultaneous or consecutive 80 explosion of which mixture in all the chambers the rotation of the movable and motor portion of the turbine being occasioned by the admission and exhaust from said chambers; the power of the turbine 85 being dependent on the shape, number and capacity of the explosion chambers to some extent, which may be varied as desired; for example by increasing the length of the openings 8, or in other words the thickness 90 of the rotor wall.

Having now particularly described and ascertained the nature of my said invention and in what manner the same is to be performed, I declare that what I claim is:

1. In an explosive turbine, a rotor having chambers formed therein at spaced intervals therearound, means for introducing a combustible mixture under pressure into said chambers in a direction to strike the side 100 walls of the chamber at an angle thereto while said rotor is rotating, means for closing said chambers, means for igniting the explosive charge within said chambers, and means for exhausting the exploded gases 105 from said chamber in a direction to cause the explosive gases to re-act against the side walls of said chamber in said rotor to add a further impetus to the rotation of the rotor.

2. In an internal combustion turbine, two spaced concentrically arranged stators and an intermediate rotor, said rotor having a series of spaced explosion chambers therein, inlet passages in one of said stators and outlet passages in the other of said stators periodically and momentarily communicating with said chambers during the normal operation of the turbine.

3. In an explosion turbine, a rotor comprising a rotary annular member having a plurality of chambers formed therein with their side walls angularly disposed to the radii passing therethrough, means for periodically introducing explosive charges 120 under pressure into each of said chambers in a substantially radial direction, while said rotor is rotating to cause the charge in entering said chambers to act directly against the side walls of the chambers and 125 130

thereby rotate the rotor, means for exploding the charges while within said chambers and means for exhausting the charges in a substantially radial direction to cause the reaction of the exploded gases in escaping from said chambers to add a further impetus to the rotation of the rotor.

4. In a direct action and reaction explosive turbine, two concentrically arranged 10 stators and an intermediate rotor, said rotor having a plurality of chambers therein leading from stator to stator and disposed at spaced intervals therearound, each of said stators having recesses in the surfaces thereof which are immediately adjacent 15 said rotor, said chambers in said rotor co-acting momentarily and periodically with the recesses in one of said stators during the rotation of the rotor to form explosion 20 chambers, means for introducing an explosive charge into each of said chambers, means for igniting said mixture in each of said chambers, said chambers in said rotor also momentarily and periodically co-acting 25 with said recesses in the other of said stators during the rotation of said rotor and after the explosion of the combustible mixture within said explosive chamber has taken place, and means for connecting said 30 last-named recesses to exhaust.

5. In a direct action and reaction explosive turbine comprising two concentrically arranged stators and an intermediate rotor, said rotor having a plurality of chambers 35 therein leading from stator to stator at spaced intervals therearound, each of said stators having in its surface which is immediately adjacent said rotor, a plurality of recesses adapted to be brought into communication with said chambers in said 40 rotor, said chambers in said rotor co-acting momentarily and periodically with the recesses in one of said stators during the rotation of the rotor to form explosion chambers, means for introducing an explosive 45 mixture under pressure into said chambers in a generally radial direction, means for igniting said mixture when in said chambers, said chambers in said rotor also momentarily and periodically co-acting 50 with the recesses in the other of said stators during the rotation of the rotor after the explosion of the mixture within the explosion 55 chambers has taken place, said exploded gases entering said chambers in a generally radial direction, means for connecting each of said last named recesses to exhaust, said rotor having a side wall of each of the 60 chambers angularly disposed with respect to the general radial direction in which the mixture enters and exhausts therefrom whereby the entrance and exhaust of said combustible mixture from said chamber will cause a rotation of the rotor.

6. A direct action and reaction explosive

turbine, comprising two concentrically arranged stators and an intermediate rotor, having its curved surfaces in contact with the inner and outer surfaces respectively of said stators, said rotor having spaced 70 chambers therein leading from stator to stator and having the side walls of said chambers disposed at an angle to the radii passing therethrough, one of said stators having passage-ways therein leading in a substantially 75 radial direction to said chambers in said rotor, and momentarily and periodically co-acting with them during the operation of the turbine to form explosion chambers, means for introducing a combustible 80 mixture under pressure into said explosion chambers whereby the combustible mixture will act directly against the walls of the said chamber in said rotor to cause the rotation of the same, the other of said stators having recesses therein leading in a substantially 85 radial direction to exhaust and positioned to be momentarily and periodically brought into communication with the chambers in said rotor after the explosion 90 within said chambers has taken place whereby, due to the disposition of the walls of said chambers in said rotor, the exploded gases will react against said walls in escaping through said recesses to exhaust to add 95 a further impetus to the rotation of the rotor.

7. In an explosive turbine, two spaced concentrically arranged stators and an intermediate rotor, said rotor having its surfaces in contact with the inner and outer surfaces, respectively, of said stators, said rotor having a plurality of chambers therein at spaced intervals therearound leading from stator to stator, said chambers having 100 their side walls angularly disposed to the radii passing therethrough, means in one of said stators for forcing a combustible mixture into said chambers in a substantially 105 radial direction to cause said mixture to act directly upon the walls of said chambers and cause the rotation of the rotor, means for igniting the mixture within said 110 explosion chambers, and means for exhausting the exploded gases from said chambers 115 through the other of said stators.

8. In an explosive turbine, a stator and a rotor each having cylindrical surfaces in contact with each other, a plurality of chambers formed in said rotor at spaced intervals therearound, said stator having a plurality of passage-ways formed therein 120 momentarily communicating with said chambers during the rotation of said rotor, said chambers and passage-ways having 125 their side walls disposed at an angle to each other when in communication, and means for introducing an explosive charge under pressure into each of said chambers in said rotor through said passage-ways in the sta- 130

tor to thereby cause said explosive mixture to strike the walls of the chambers in said rotor at an angle thereto and thereby rotate the same.

5 9. In an explosive turbine, a stator and a rotor having surfaces in contact, said rotor having a plurality of chambers formed therein at spaced intervals therearound, said stator having a plurality of exhaust

10 passages formed therein at spaced intervals therearound and momentarily and periodically communicating with said chambers during the rotation of the rotor, means for admitting and exploding an explosive

5 charge in each of said chambers in said rotor while said rotor is rotating, the walls of said passages and the walls of said chambers being disposed at an angle to each other whereby when said chambers are brought

20 into communication with said passages the reaction of the exploded gases in escaping will cause the rotation of the rotor.

10. An internal combustion turbine including relatively movable parts, one of

25 which is rotatable, some of said parts having cavities therein adapted to be momentarily and periodically opened into each other to form explosion chambers, walls in said chambers being obliquely disposed with respect to radial lines extended through points in said walls, means for introducing a combustible composition into said chambers, said means including a tube disposed substantially in the axis of said rotatable part,

30 means for igniting said composition, and means for exhausting the products of combustion from said chambers.

11. An internal combustion turbine including relatively movable parts, one of

40 which is rotatable, some of said parts having cavities therein adapted to be momentarily and periodically opened into each other to form explosion chambers, walls in said chambers being obliquely disposed with respect to radial lines extended through points in said walls, means for introducing a combustible composition into said chambers, said means including a rotatable member disposed substantially in the axis of said rotatable part,

45 means for igniting said composition, and means for exhausting the products of combustion from said chambers.

50 12. An internal combustion turbine including relatively movable parts, one of

which is rotatable, some of said parts having 55 cavities therein adapted to be momentarily and periodically opened into each other to form explosion chambers, walls in said chambers being obliquely disposed with respect to radial lines extended through points 60 in said walls, means for introducing a combustible composition into said chambers, said means including a rotatable, apertured member disposed substantially in the axis of said rotatable part and means for rocking 65 said rotatable member about said axis, means for igniting said composition, and means for exhausting the products of combustion from said chambers.

13. An internal combustion turbine including 70 relatively movable parts, one of which is rotatable, some of said parts having

cavities therein adapted to be momentarily and periodically opened into each other to form explosion chambers, walls in said 75 chambers being obliquely disposed with respect to radial lines extended through points in said walls, means for introducing a combustible composition into said chambers, said means including a tube, axially disposed in the turbine, said tube having apertures in the sides thereof adapted to be aligned with some of said cavities, means for imparting a rocking movement to said tube,

80 means for varying the amplitude of such 85 rocking movement, means for igniting said composition, and means for exhausting the products of combustion from said chambers.

14. An internal combustion turbine which comprises two fixed parts and a rotor mov- 90

able therebetween, said parts and said rotor having cavities adapted to co-act to form explosion chambers, means for introducing an explosive composition into said chambers, said means including a central admission 95 tube, an apertured plug carried thereby, the apertures in which are in communication with the interior of said tube, means for longitudinally displacing said plug and tube, means for throttling the flow of fluid through 100 said tube, and means for igniting said composition when in said chambers.

In testimony whereof I affix my signature in presence of two witnesses.

JEAN JACQUES HEILMANN.
